[57] ABSTRACT

This machine straps a package with flexible tape strap-

ping. A strap is initially fed by feed and tension wheels around the yoke and against a stop with which a gripper clamps the free end of the strap against an anvil, the feed is reversed to remove a slack loop in the strap at the feed mechanism and the feed mechanism is automatically stopped. Thereafter, a tensioning valve is operated to reactivate the feed mechanism so as to slip the strap out of the yoke, tension the strap around the package and join the ends of the strap after tensioning. Occasionally the apparatus malfunctions to produce a short feed, wherein during the initial feeding operation, the strap does not reach the gripper so that even though the gripper closes against its anvil, when the feed mechanism is restarted to tension the strap, the strap is pulled out of the yoke, instead of being tensioned around the package and hence must be rethreaded. To prevent this, an air orifice is provided at the gripper anvil which orifice is not covered by the free end of the strap when the aforesaid short feed malfunction occurred, and the gripper was closed and this short feed condition prevents restarting of the feed mechanism in the tensioning direction when the aforesaid valve is operated to initiate tensioning. Thus, the strap is not withdrawn from the yoke and after the obstruction is cleared the strap need not be re-threaded through the machine.

STRAPPING MACHINE WITH SHORT FEED LOCKOUT

FIELD OF THE INVENTION

This invention relates to apparatus for strapping articles such as packages and more particularly to improvement in such apparatus which eliminates the need for rethreading the machine in case the strap is not fed completely before the strap tensioning cycle is initiated.

DESCRIPTION OF PRIOR ART

The apparatus of the present invention is an improvement over the U.S. Patent to Goodley No., 3,759,169, issued Sept. 18, 1973, and assigned to the FMC Corporation. Although the short feed sensing and lockout device of the present invention can be applied to other strapping machines, a brief explanation of the invention will be provided as it is applied to the machine of the aforesaid Goodley patent.

SUMMARY OF THE INVENTION

A strapping machine to which the present invention is applied is described in detail in the aforesaid Goodley patent and enough of this exemplary machine will be referred to in order to provide a complete understanding of the invention in a detailed description that follows.

Briefly, in the aforesaid strapping machine the strap is fed by cooperating feed and tension wheels (driven by a reversible air motor) between a rear gripper and an anvil, through a yoke between a front gripper and the anvil and up against a stop at the anvil. This feed is initiated by the operation of an on-off valve. When the strap engages the aforesaid stop, a loop of excess strap develops at the feed mechanism which loop is sensed and causes the front gripper to clamp the strap end against the anvil as well as automatic initial reversal of the feed mechanism (in the tensioning direction) to remove the loop and upon removal of the loop, the initial reverse operation of the feed mechanism automatically stops. Now, if a package is in place within the yoke, a second or tensioning valve is operated (manually in the example given) which causes the feed mechanism to restart in the tensioning direction, pulling the strap clear of the yoke and tight around the package. Since the free end of the strap has been gripped by the front gripper against the anvil this prevents the strap from simply sliding out through the yoke during tensioning. With the free end of the strap thus held, the tensioning operation causes the strap to be pulled radially free of clips in the yoke and to be wrapped around and tensioned on the package, whereupon the second gripper clamps the running end of the strap against the anvil and the two ends of the strap are joined (as by heat sealing) to hold the strap in tension on the package.

Occasionally a malfunction, termed a "short feed", occurs in that during the initial feeding operation initiated by the aforesaid on-off valve, the free end of the strap may strike an obstruction (such as foreign matter within the yoke) before the end of the strap passes between the front gripper and the anvil and engages the stop. Excessive curl of the strap may also give the effect of an "obstruction". When this short feed condition occurred, the prior machine was unable to discriminate between the obstructed condition and the normal con-

dition wherein the strap end has passed between the front gripper and the anvil and against the stop. Since a loop will develop at the feeding mechanism whether the strap encounters an obstruction in the yoke, or reaches the stop as in normal operation, the feeding mechanism is stopped and initially reversed to remove the loop, whereupon it stops again. However, under a short feed condition, if the second or tensioning valve (which is a foot operated valve in the illustrated embodiment) is now depressed to restart the feeding mechanism in the reverse or tensioning direction, since the free end of the strap has not been gripped between the front gripper and the anvil, the strap will be pulled back through the yoke and if this pseudo-tensioning action is not stopped soon enough, the strap will be pulled through and out of the feeding mechanism itself. Thus in the prior machine, the first indication that an operator had that the device was not feeding properly was that the strap pulled through the yoke and feed mechanism during what should have been a tensioning operation. Thus in addition to finding the original cause of the malfunction during the feeding operation, the operator must rethread the machine, that is, the strap must be reintroduced into the feed mechanism and through the gripper and anvil structure before normal operation can be resumed.

In accordance with the present invention, the initial feeding of the strap, stopping the feed, and initially reversing the feed to remove the loop at the feeding mechanism takes place as before, upon depressing of the on-off valve. However, when the aforesaid tensioning valve which is provided to initiate the final tensioning operation is depressed, the present invention disables or locks out the feed and tensioning mechanism so that the latter cannot be restarted in the tensioning direction and hence will not pull the strap clear of the mechanism. The preferred method of attaining the aforesaid feature and advantage of the present invention involves a simple addition to an air valve pilot circuit that controls the reversible air motor for the feed mechanism. Briefly, when the tensioning valve is operated to initiate the final strap tensioning mechanism after strap feeding has been completed, a pilot-operated valve is shifted which directs air to the air motor (under normal conditions) to initiate the tensioning operation. Under the present invention, the anvil for the front gripper that normally grips the free end of the strap is provided with an air orifice and when the strap is fed between the front gripper and the anvil and the front gripper closes, this anvil orifice is blocked or closed off by the end of the strap and final tensioning will take place upon operation of the aforesaid tensioning valve. However, when the strap end does not reach the aforesaid front gripper and anvil, even though that gripper is closed as usual, since the gripper has a serrated jaw, the aforesaid orifice in the anvil is not blocked and hence air will escape from the anvil orifice when the aforesaid tensioning valve is operated to initiate final tensioning. This escape of air from the anvil orifice bypasses a sufficient amount of air from the aforesaid pilot operated valve that is provided to reverse the feed motor and initiate tensioning so that the valve pilot does not shift the pilot operated valve, as in normal operation. Under this short feed condition, even though the manually operated tensioning valve is operated to initiate tensioning, the motor which drives the feed and tensioning wheels does not restart in the

tensioning direction and nothing happens to the strap. Thus, the fact that when the operator depresses the valve to initiate tensioning, the motor does not start in reverse but remains stationary, provides an indication to the operator that there is an obstruction or other malfunction which has prevented full feeding of the strap between the front gripper and the anvil. Thus, the operator is made aware of failure of the apparatus to fully feed the strap and investigation can be made to remove or clear the obstruction. Once the obstruction is removed or cleared, steps can be taken to re-start the feed apparatus to complete the feed and this is accomplished without need for rethreading the strap through the apparatus, as would be the case of the tensioning cycle had been initiated when the manually operated valve provided for initiating that operation was operated.

In the preferred form of the invention, an adjustable needle valve is provided between the valve that initiates tensioning and the pilot for the valve that controls the air motor for reverse operation. The anvil orifice passageway is in parallel with that needle valve and the needle valve is adjusted so that although there is a direct air passage from the manual valve to the pilot operated control valve (through the needle valve), the needle valve does provide a sufficient obstruction to prevent pilot operation of the control valve when the anvil orifice is open and hence bypasses some air from the needle valve. On the other hand, the needle valve is also adjusted so that when the anvil orifice is closed, as is the case when the front gripper closes against the free end of a strap, sufficient air will reach the pilot of the control valve to initiate the tensioning operation.

Thus under the disclosed embodiment of the present invention, short feed lockout is provided by adding a simple orifice and a needle valve to the air control circuit for the feed and tensioning motor.

BRIEF DESCRIPTION OF THE DRAWINGS

FIG. 1 is an overall perspective view of a strapping machine embodying the invention.

FIG. 2 is a horizontal section of the machine taken as looking in the direction of arrows 2 — 2 of FIG. 1 and with parts broken away.

FIG. 2A is a schematic diagram showing the normal threading of strap through the machine.

FIG. 3 is a perspective of the feed and tensioning mechanism.

FIG. 4 is a side view of the front of a machine with parts broken away.

FIG. 5 is an enlarged fragmentary longitudinal section taken on line 5 — 5 of FIG. 2.

FIG. 6 is an enlarged transverse section taken on line 6 — 6 of FIG. 2.

FIG. 7 is an enlarged front view of the improved anvil with the grippers shown in phantom.

FIG. 8 is a partial section through the improved anvil taken along the sensing air passages in the anvil.

FIGS. 9 — 13 are schematic control diagrams showing normal operation when a strap reaches the front gripper.

FIGS. 14 — 22 are operational schematic diagrams showing salient mechanical features of the invention as operating in accordance with the control diagrams of FIGS. 9 — 13 during normal operation.

FIG. 23 is a control diagram like that of FIG. 11 illustrating automatic stopping of the reverse drive after the

feed loop has been removed but when the strap has encountered an obstruction.

FIG. 24 is a control diagram like that of FIG. 12 but showing the operation when the foot valve is opened to tension the strap, but the latter met an obstruction.

FIG. 25 is an enlarged mechanical diagram illustrating the condition of control diagram FIG. 23 when an obstruction is encountered.

FIG. 26 is a still further enlarged section through the front gripper and anvil under the conditions of FIGS. 23 and 25.

FIG. 27 is a greatly enlarged section through the front gripper and anvil under the conditions of control diagram FIG. 24.

DETAILED DESCRIPTION

As mentioned, the preferred embodiment of the invention will be described as fitted to the strapping machine of the aforesaid Goodley application, Ser. No. 198,862, the disclosure of which is incorporated herein by reference. However, enough of the salient features of the machine will be herein described to provide a complete understanding of the invention. Various details such as operation of the linear cam and the electric circuits, not essential to an understanding of the present invention, are omitted but are explained fully in the aforesaid Goodley application.

Mechanical Features of the Strapping Machine

Referring to FIG. 1, the strapping machine of the present invention includes a main body of housing 12 supported on legs 13 and mounting a flat upper table 14. The table is slotted at 16 to accommodate tensioning of a strap around a package (not shown) on the table. A retractable anvil 18 (see also FIGS. 6 — 8) is at the center of the table 14. The strap S is fed from a tape reel in a manner to be described in detail presently around a yoke 20 that surrounds the package. The yoke has a radially inwardly opening slot to release the strap for tensioning. After the feed, the free end of the strap is gripped, the strap is tensioned against the package, the running portion of the strap is gripped, a heat sealed joint is made, the running portion of the strap is cut and the strapped package removed.

Machine operation is initiated by switching an ON-OFF valve 22 to ON and the valve is left in that position during normal operation, and as explained in the aforesaid Goodley patent, after a package has been strapped, a new strap feeding cycle is automatically indicated.

A foot valve FV is provided, which is depressed by the operator to initiate a strap tensioning cycle, and the present invention is closely associated with the operation of the valve, or its equivalent.

The break away plan view of FIG. 2 shows additional mechanical features. The anvil 18 is broken away in this view as is a retractable tongue 24 (best seen in FIG. 6) to expose a vertically reciprocating platen 26 that mounts a strap cutting knife 27 (see FIG. 5).

FIG. 2 also shows a heat sealing blade assembly indicated generally at 28 and illustrated in its retracted position. A side view of the blade appears in FIG. 6. Details of the platen 26 and the heat seal blade 28 are not critical to the present invention. Also appearing in FIG. 2 are a front gripper 30 and a rear gripper 32 for holding the ends and the bight of the strap respectively.

These grippers are operated by bell cranks, as seen in FIG. 5.

A strap transport mechanism in the form of a pair of geared together feed and tension wheels appears in FIG. 3. The strap S enters from below and is wrapped partially around a feed wheel 34, pinched between that wheel and a tension wheel 36, wrapped around the tension wheel and fed on through the mechanism.

FIG. 2A (a simplified diagram) shows the path of a strap through the apparatus. The strap enters the feed wheel 34 from the strap reel (FIG. 1) passes between the feed and the tension wheels 34, 36, wraps around the tension wheel 36, passes beneath the gripping face of the front gripper 30, passes beneath the tongue 24 and above the platen 26, passes between the rear gripper 32 and the anvil 18, is threaded through the yoke 20, passes between the front gripper 30 and the anvil 18, passes between the tongue 34 and the anvil 18, and abuts a stop 19 formed on the anvil.

Strap Transport Drive

Referring principally to FIGS. 2, 3 and 4, a reversible air motor M has a sprocket 40 (FIG. 3), driving a chain 42 and a sprocket 44 on the shaft 46 for the tension wheel 36. The other end of the shaft 46 mounts a gear 48 which is meshed with a gear 50 of the same pitch diameter on the shaft 52 for the feed wheel 34. The feed and tension wheels 34, 36 are covered with friction bands. The strap S is gripped between the wheels 34, 36, but it wraps around the feed wheel 34 for something over 90° and around the tension wheel 36 for something over 180°. The wrap around the feed wheel 34 is adequate to feed the strap through the path shown in FIG. 2A and the wrap around the tension wheel 36 is adequate to tightly tension the strap around the package before sealing the joint in the strap.

In order to operate a tension limit valve TV, for stopping the tensioning of the strap around the package, and to initiate other functions, an idler sprocket 60 (FIGS. 3 and 4) is mounted on an arm 62 pivoted to the frame at 63 (FIG. 4) and pivotally mounts a clevis having a switch operating rod 64. A compression spring 66 that is compressed between a nut on the rod 64 and a frame element 67 (FIG. 4) is used for taking up the slack in the chain 42. The idler rod 64 also mounts a tab 65 (FIGS. 3 and 4) which is normally spring urged against the operating button of the tension limit air valve TV, the construction being that the valve TV is closed when there is slack in the reach 42a of the chain 42 engaged by the idler sprocket 60. This slack occurs when the motor M is driving the wheels 36, 34 in the feed direction illustrated by the solid arrow on the feed wheel 34 in FIG. 3. The slack tends to be removed from the idler run 42a of the chain 42 when the motor M is reversed to drive the tension wheel 36 in the tension direction indicated on that wheel by the dashed arrow in FIG. 3. When the strap is tight around the package, the run 42a of the chain becomes taught, swinging out the idler arm 62, and pulling the tab 65 away from the tension limit valve TV. This shifts a pilot operated air valve for stopping the motor M and for other purposes to be described presently. Opening of the valve TV only takes place upon the generation of a predetermined amount of torque required to drive the tensioning wheel 36, which torque is sufficient to adequately tension the strap around the package. Hence, the action just described does not stop the motor M from driving

in the tensioning direction until the package is tightly strapped.

Overrun Flag

5 As described in detail in the aforesaid Goodley patent and as shown schematically in the control diagrams such as FIG. 9, and in the mechanical diagrams of FIGS. 14, 16, 18 and 20, an overrun flag 70 is provided at the tension wheel 36 for sensing a loop in the strap that develops during the feeding operation and for initially reversing the motor M for causing the loop to be automatically removed and the motor stopped before the strap is tensioned about an article, by operation of the foot valve FV.

10 The flag 70 has a fixed pivot 70a (FIG. 14) and has a loop sensing surface 70b that is contoured to fit the tension wheel 36. The flag 70 has a cam surface 70c for operating a cam follower 71. The follower 71 has a fixed pivot 71a and has a follower roller 71b for engaging the cam surface 70c of the flag 70. The follower 71 has a cam surface 71c for permitting the operating arm 72 of a strap limit valve SV to open, which occurs when the flag 70 is displaced by development of a loop (FIGS. 16 and 18) and as will be explained in detail presently.

15 FIGS. 2, 3 and 5 show some details of the strap guide mechanisms, details of this structure not being critical to the present invention. The strap wraps something over 90° around the feed wheel 34 (FIG. 3), passes between the nip of the wheels 34 and 36 wrapping more than 180° around the tension wheel 36. The strap leaves the tension wheel 36 and passes over the top of the upper surface of a plate 77 (FIG. 5) passes through 20 a slot 30a in the front gripper 30, through a throat 31 in the platen housing, passes between the tongue 24 and the platen 26, passes between the rear gripper 32 and the anvil 18, beneath spring release guide 80a, 82a (FIG. 2) and on through the yoke 20. After emerging 25 from the yoke, the strap rides over the upper surface of a shoe plate 78 (FIG. 5), beneath a pair of spring loaded release guide rails 80, 82 (FIG. 2) between the front gripper 30 and the anvil 18 (FIG. 5) and on to the stop 19 on the anvil 18 as previously described. An upward pull of the strap S will spread the guides 80, 82, 30a and 82a and permit the strap to become free of the guide structure during tensioning of strap about the package. Similar release devices are provided about the yoke 20, as described in detail in the aforesaid Goodley 35 patent. The purpose of these releases is to permit the strap to be pulled radially clear of these guides during final tensioning about a package whereupon the strap is also pulled up through the slot 16 in the table 14 (FIG. 1) and against the package.

40

Anvil

45 Referring to FIGS. 7 and 8, the anvil 18 of the present invention is like that of the aforesaid Goodley patent but has been improved to incorporate in air jet orifice for sensing the presence or absence of a strap end between the first gripper 30 and the anvil.

50 The anvil 18 has a horizontal platform portion 90 with a beveled nose. The platform 90 has an under surface 92 for cooperation with the front gripper 30 and an offset under surface 94 for cooperation with the rear gripper 32, these surfaces being jointed by the aforesaid strap stop shoulder 19.

55

The anvil is pivotally mounted for side retraction by means of side arms 95 and 95a (FIG. 7) which are mounted on pivot bolts 96, 96a secured to a fixed frame portion of the machine which also forms a slide housing for the platen 26, (FIG. 5). Torsion springs 97 (one of which is shown in FIG. 7) are connected between the frame and the arms 95, 95a of the anvil (FIG. 5) for urging the anvil toward its inward or advanced position of FIG. 6. An anvil operating finger 98 projects rearwardly from the anvil arm 95 (FIG. 8) which finger serves as an operator for retraction of the anvil by a pivoted double bell crank 99, pivoted to the frame at 99a (FIG. 7) and operated by a tongue-anvil cam portion of a composite linear cam 100, which in turn is operated by a linear actuator 102 (FIGS. 5 and 9), as described in detail in the aforesaid Goodley application.

FIGS. 5 and 6 show the anvil in its advanced or "in" position for cooperation with the grippers 30, 32 during tightening of the strap and the anvil is retracted for removal of the strapped package, by the tongue-anvil cam section of the composite linear cam 100.

The air jet passage for sensing the presence or absence of a strap end between the front gripper 30 and the under surface 92 of the anvil 18 is formed in the anvil as shown in FIGS. 7 and 8. The anvil is drilled at 103 to provide the orifice outlet. A slightly diagonal drilling 104 in the platform portion 90 of the anvil connects with a vertical drilling 105 in the anvil arm 95, which connects to a tapped hole 106. The latter receives a hose fitting 107 for an air hose 108 that is connected to the source of compressed air for the air circuit. The drillings are plugged as seen in FIG. 8 and the drillings 103, 104 and 105 are shown in the same plane in that figure for clarity of illustration. The operation of the sensing orifice will be explained in detail later, in connection with control diagrams such as FIGS. 12 and 24, as well as FIGS. 25 - 27.

Tongue

The tongue, indicated generally at 24, serves as a retractable guide between the end of the strap and the bight of the strap as seen in FIG. 5, but the tongue is retractable so that the heat sealing blade 28 can be inserted in the space previously occupied by the tongue.

As seen in FIG. 6, the tongue 24 has a thin terminal flange 110 that lies beneath the anvil surface 92 and above the top of the platen 26 to provide two spaces for passing the strap (FIG. 5). The portion 110 is joined to a thicker portion 112 in a manner which forms a shoulder for engaging a complimentary shoulder formed on the anvil 18, so that retraction of the anvil also retracts the tongue, as described in the aforesaid Goodley patent.

The tongue portions just described are pivotally mounted by side arms 116, 117 (FIGS. 2, 5, 6 and 7), these arms being pivotally mounted on the bolts 96, 96a that mount the underlying support arms 95, 95a for the anvil. The tongue is urged toward its inward or advanced position by a tension spring 118, connected between a finger 118a on the tongue structure (FIGS. 2 and 5) and a fixed cross plate 119 (FIG. 2) within the main housing 12. The tongue 24 is mechanically retracted independently of the anvil 18 by depressing a finger (not shown) projecting from the tongue side arm 116 and operated by the left side of the aforementioned bell crank 99 (FIG. 7), as described in detail in the

Goodley patent. Details of this structure are not critical to the present invention.

Platen

5 The platen 26 is raised, first to squeeze the strip parts against the sealing blade and then to squeeze the heated joint after retraction of the heat sealing blade 28, to make the seal. As best seen in FIGS. 5 and 6, the platen slides vertically in a fixed housing portion 120, 10 previously mentioned and the platen 26 carries the knife 27 for severing the running or bight end of the strap after the strap has been tightened around the package and the joint formed.

The platen 26 is actuated in a manner which gives resilient relief upon cam lifting thereof against the joint. To this end a lower portion 130 of the platen assembly (FIGS. 5 and 6) is slidably mounted in the housing 120 and on a bolt 132 screwed into the platen 26, and the platen parts 26, 130 are urged apart by a compression spring 134. The lower platen element 130 carries a cam follower roller 136 for operation by a linear platen cam forming one of the cams on the linear cam assembly 100. Thus when the platen 26 is squeezed up against the strap portions to form the joint, slight overtravel of the lower platen portion 130 in response to the platen cam will be accommodated by the spring 134.

25 The platen assembly 26, 130 is urged downwardly to hold the platen roller 136 against its cam by a tension spring 138 connected to a spring post 139 on the platen and a fixed anchor 139a (FIG. 6).

30 The details of the platen operation are not critical to the present invention, and in case the strapping machine does not employ apparatus of the type shown for making the joint, both the platen 26 and the heat seal blade 28 may be modified or equivalents substituted, 35 without affecting the mode of operation of the short feed sensing device of this invention.

Heat Seal Blade

40 The heat seal blade assembly 28 includes a thin, sinusous resistance element or blade 140 (FIGS. 2, 4 and 6), the details of which are not critical to the present invention. In fact, and as previously noted, the present invention has utility whether or not the strapping machine is of the type that employs a heat seal blade. The resistance element 140 is mounted on a swinging arm 146 (FIG. 6) pivoted at 147 to frame structure 148 in the main housing. The blade assembly 28 is cammed in and out by a blade arm cam on the linear cam assembly 100 and is held in its retracted position during one stroke of the linear cam assembly 100, by a blade hold out 149. The arm is spring urged into the heat sealing position by a torsion spring 150 whose arms engage the blade arm 146 and the frame portion 148. The blade arm 146 is controlled by a cam follower roller 152 (FIG. 6) secured to a bracket 152a on the arm 146. For a complete description of the blade cam and holdout during the blade operating cycle, reference is made to the aforesaid Goodley application.

Grippers

55 When the strap is fed properly through the yoke, its free end passes over the front gripper 30 and when closed, the front gripper 30 grips the free end of the strap against the under surface 92 of the anvil 18. The foot valve FV is operated, whereupon the strap is tensioned around the package by the tensioning mecha-

nism and the rear gripper 32 thereafter grips the bight or running part of the strap against the under surface 92 of the anvil. The gripping jaw of the front gripper 30 is corrugated at 30b (FIG. 27) and the jaw extends from the free end of an arm 153 of a bell crank 154 pivoted at 155 to ears projecting from a fixed plate 156 (FIG. 5). The lower arm 157 of the gripper bell crank 154 is urged to hold the front gripper 30 in its retracted or open position by a compression spring 158 (FIG. 5) compressed between a nut 159 on a bolt 160 mounted in the plate 156 and the lower end of the gripper bell crank arm 157.

The front gripper jaw 30 is raised to grip the free end of the strap against the anvil by a pneumatic diaphragm actuator indicated generally at 164 (FIG. 5) which actuator has a diaphragm 165 secured in air tight relation to the frame plate 156. The diaphragm 165 actuates the bell crank 154 through a screw 166 that protrudes into a hole 167 in the bell crank arm 157. An air chamber 168 for the diaphragm 165 is formed in the mounting plate 156, and is connected at 169 to valves as shown in the control diagrams such as FIG. 9.

Diaphragm actuators of this type are well known in the art and details thereof are not critical to the present invention. In fact, the actuator could be replaced by a piston and cylinder assembly, if desired.

The rear gripper 32 grips the bight or running portion of the strap S against the under surface 94 of the anvil 18 (FIG. 5). The parts of this gripper correspond to those of the front gripper and hence corresponding reference numbers with the letter (a) appended, are utilized for these gripper parts.

Linear Actuator and Cam Assembly

As previously mentioned, the anvil, 18, tongue 24, 35 platen 26 and the blade 28 and a cam limit valve CL (FIG. 9) are all mechanically operated by the linear actuator 102 and the linear cam assembly 100. The linear actuator 102 is a double acting pneumatic cylinder and piston assembly and the piston rod of the cylinder and mounts the cam block assembly 100 which supports a tongue-anvil cam 180 (FIG. 7), a platen cam 182 (FIG. 5), a heat seal blade arm, cam 184 and carries the blade hold 149, previously mentioned. The tongue-anvil cam 180 operates the tongue-anvil bell crank 99 (FIG. 7). The blade arm cam 182 operates the blade follower roller 152 (FIG. 6). The cam block itself has rear and lower slide surfaces guided by rollers 192, 193, on the frame post 148 (FIG. 6), which absorb the thrust of the various springs and cam follower rollers actuated by the respective cams. When the cam block assembly 100 is in its fully retracted position, it opens a cam limit valve CL (FIGS. 4 and 9) for reinitiating a feed cycle of the strap, as will be described presently. The details of the linear cam assembly 100 are not critical to the present invention and reference is made to the aforesaid Goodley patent for the various constructions involved.

Control Circuit Elements

Before describing the critical sequences of a normal and of an abnormal operational cycle, the more significant control elements will be briefly mentioned in order to avoid interrupting the cycle description with a characterization of these elements. The principle control elements are shown in the control diagram of FIG. 9 (for example). Certain electrical circuits includ-

ing those relating to the timing of the operation of the linear actuator 102 for the cams 100 are omitted from FIG. 9 as not critical to the invention, and reference is made to the aforesaid Goodley patent for a complete description thereof.

On-Off Valve, 22

This valve, under control of the operator, is provided in order to set up an air supply to certain elements of the control system when the machine is ready for operation, and is usually left in that position.

Foot Valve — FV

This is a spring closed three way valve that is momentarily opened by the operator. Its function is to initiate tensioning of a strap about a package after the strap has been fed through the yoke and under the front gripper, and is the only control required for operation of the machine once it is started by the on-off valve 22.

Strap Limit Valve — SV

This is a spring closed three way valve that is operated by the tension wheel flag 70. It has the following functions:

- Stops the feed.
- Closes the front gripper 30.
- Reverses the feed motor to withdraw the overfeed loop.
- Stops the feed motor reverse when the loop is withdrawn.

Tension Limit Valve — TV

This is a three way valve that is spring opened and mechanically closed by the chain idler 60 and the rod 64. Under the present invention, if the strap meets an obstruction during feed final tensioning cycle is locked out and hence the tension limit valve portion of the apparatus is not set into operation.

Its functions are:

- Stop the tensioning drive after the strap is tensioned around the package.
- Start linear cam actuator advance.
- Close the rear gripper.
- Start a timer for subsequently retracting the linear actuator.

Cam Limit Valve — CL

This is a three way valve that is spring closed and mechanically opened by the linear actuator cam block assembly 100. Its function is to start the feed upon retraction of the linear actuator and to prevent inadvertently restarting the feed until the actuator has fully advanced and retracted.

Valves V-1, V-2

These are four way valves, air pilot positioned in either direction. After having been operated by one pilot, 60 they remain in that position until they respond to the opposite pilot.

Valve V-3

This is a three way, double pilot operated valve. When operated by the pilot p-2 in one direction this operation is spring assisted to override any counter-pressure that might be placed on the other pilot, p-1.

Valves V-4, V-5

These are three way valves and are spring urged in one direction and pilot operated in the other direction.

Valve V-6

This three way valve is spring urged in one direction and solenoid operated in the other direction.

Indicated on the diagram are variable throttle valves t.v. of conventional design which can control the flow of air therethrough in accordance with their adjustment.

Also shown are shuttle valves SV-1 and SV-2 which are of conventional design and provide the usual and known shuttle valve function.

PE-1, PE-2

These are pressure operated electric switches. As mentioned, details of the wiring for the electric switches embodied in these units are not critical to the present invention and hence their exact wiring connections are omitted from the drawings.

Needle Valve, NV

This valve related to the short feed sensing improvement of the present invention and will be described presently.

Operation of a Cycle — Normal Feed

The operation of the strapping machine of the present invention during one cycle will be described in connection with the control diagrams of FIGS. 9 - 13 and the mechanical diagram of FIGS. 14 to 22. There is not always a one to one correspondence between the mechanical operational diagrams of FIGS. 14 - 22 and the control diagrams of FIGS. 9 - 13 because such a correspondence would result in unnecessary duplication of figures.

Ready to Start

FIG. 9 shows the circuit conditions before the on-off valve is operated to start the machine, and it will be assumed that the strap S has been threaded between the feed and tension wheels 34, 36. The package P may or may not be on the machine table at this time. It will be assumed that the electrical control circuit is energized and that an air supply has been connected to the air supply lines AS, leading to the various valves in the control circuit.

When the on-off valve 22 is in its off condition (not shown), the pressure switch PE-1 is not pressurized. As shown in the aforesaid Goodley patent, the switch of PE-1 is closed when PE-1 is not pressurized and the switch is in series with the solenoid operator for the valve V-6 across the electrical line. Thus when PE-1 is not pressurized, its switch is closed and the solenoid for air valve V-6 is energized. This shifts the valve V-6 against its spring so that the air supply admits air to the pilots p-1 for both valves V-1 and V-2, positioning them as shown in FIG. 9. The output port 1 of the valve V-2 directs air to the rod end of the linear actuator cylinder 102, which was either already in its retracted position or immediately returns to that position. When the cylinder 102 is in the retracted position shown in FIG. 9, the cam block 100 mechanically holds the cam limit valve CL in its open position shown, but before the on-off valve is opened, no air is directed to the cam limit

valve CL but that valve is mechanically positioned for the next operational step. The strapping machine is now ready to initiate strap feeding.

Strap Feeding

FIGS. 9A and 14 illustrate the strap feeding portion of the cycle. Referring now to the conditions actually shown in FIG. 9A, the operator has moved the on-off air valve 22 to its on position and normally it will be left in this position during operation of the machine over a series of complete cycles. Air is now admitted to the pressure switch PE-1, which opens the aforesaid normally closed contacts of PE-1 (not shown), de-energizing the solenoid for valve V-6, so that the spring 15 shifts V-6 to the position of FIG. 9A. This connects the pilots p-1 for both valves V-1 and V-2 to exhaust, but these valves will remain in the positions of FIG. 9A to which they had previously been shifted, until their pilots p-2 receive air.

When the on-off valve 22 is opened, air under pressure is admitted to the valve V-1 and its output body port 1 conducts air through the cam limit valve CL (held open by the linear actuator cam block 100) thereby admitting air to the pilot p of the valve V-4, 20 which is thereby opened. Air from the air supply now passes through an adjustable throttle valve t.v. and through the valve V-4 to the "feed" port of the reversible drive air motor M. As seen at the upper right of FIG. 9A, and in FIGS. 14 and 15, during the normal feeding process the strap is fed through the channels, including the slot 30a in the front gripper 30, between the tongue 24 and the platen 26, between the rear gripper 32 and the anvil 18 and around the yoke 20. If all goes well, the end of the strap enters between the open front gripper 30 and the anvil 18 and continues on towards the stop 19 on the anvil 18 (FIG. 15).

Strap Limit Valve Actuation

In FIGS. 16 and 17, the strap has been fed until its end strikes the stop 19 on the anvil 18. Rotation of the wheels 34, 36 continues, develops an overfeed loop of strap develops at the tension wheel 36 behind the flag 70. This loop pivots the flag 70 to the right as seen in the FIG. 16, to an intermediate "stop feed" position illustrated in broken lines. At this position, the flag 70 and its follower 71 have moved the strap limit valve operator 72 to a position wherein the strap limit valve SV is open.

Referring to control diagram of FIG. 10, when the strap limit valve SV opens, air is admitted to the pilot p-2 of valve V-1 which shifts that valve and opens the pilot p of the valve V-4 to exhaust through the cam limit valve CL and through the body port 1 of the valve V-1. This exhaust of the pilot p of the valve V-4 causes V-4 to close by spring action, exhausting the air line to the drive motor M that cause motor rotation in the feed direction. Simultaneously, air from the strap limit valve SV passes through the shuttle valve SV-2 to the reverse line for the motor M, but due to the momentum of the parts, reversal of the motor is not accomplished instantly and there is some overtravel of the flag 70, as indicated in solid lines in FIG. 16. Also, at this time, the body port 2 of the valve V-1 admits air to the front gripper diaphragm 164, closing the front gripper 30 thereby holding the free end of the strap against the anvil so that it cannot be withdrawn until the gripper 30 is re-opened.

Loop Withdrawal

The motor M reverses and begins to withdraw the loop of slack from in front of the flag 70, as indicated in FIG. 18. This loop withdrawal continues until the flag 70 has returned to its initial condition and the strap limit valve SV is reclosed, as will be described in connection with the diagram of FIG. 11 and FIG. 20.

Strap End Sensing

Referring to FIG. 17 (also shown in FIG. 19), during a normal feed application the end of the strap S passed over the front gripper 30 and was tightly pressed against the under surface 92 of the anvil 18. The strap end now blocks the air orifice 103 in the anvil, and as will be seen, when the orifice 103 is closed, it is possible to initiate tensioning of the strap about the package by means of the foot operated tensioning valve FV.

Loop Withdrawal Stopped

Referring to the control diagram of FIG. 11, upon withdrawal of the slack loop at the flag 70, the strap limit valve SV re-closes and exhausts air from the reverse or tension drive line of the motor M and stops the initial reverse of the motor, so that the strap remains positioned about the wheels 34, 36 as shown in FIG. 20. Also as seen in FIG. 11, the pilot p-2 of valve V-1 is exhausted, but this valve remains in its previous position, conducting air from its body port 2 to hold the front gripper 30 closed, as well as directing air to a line leading to the valve V-3, although this air line is blocked at the latter valve. If not already present, a package P can be placed on the table of the machine ready for the strapping operation.

Strap Tensioning

In order to tension the strap about the package P the foot operated valve FV is opened by the operator, as indicated in the control diagram of FIG. 12. This admits air through the adjustable needle valve NV, which has been added to the air circuit of the aforesaid Goodley patent, in accordance with the present invention. The needle valve NV is adjusted so that when the anvil orifice 103 is blocked by the strap end pressed between the front gripper 30 and the anvil (FIGS. 17 and 14), the needle valve passes enough air through the shuttle valve SV-1 and to the pilot p-1 of the valve V-3, to shift the valve V-3. The pilot p-2 of the valve V-3 is exhausted through a previously established connection through body port 2 of the valve V-2. It will be recalled that valve V-3 had previously received air from body port 2 of the valve V-1 (FIGS. 10 and 11), so that now this air is conducted by the valve V-3 to the pilot p of the valve V-5 which shifts and admits air from its air supply AS through an adjustable throttle valve t.v. and through a shuttle valve SV-2 to the tension or reverse port of the reversible air motor M. The reverse or tensioning speed of the motor M is controlled by an adjustable needle in the valve t.v. associated with the valve V-5.

With motor running in the tensioning direction as just described, the tension wheel 36, as seen in FIG. 21, now rotates in the direction to pull the strap clear of the yoke clips (not shown) and starts to draw the strap around the package P. The excess strap thus developed can be directed to an accumulator (not shown) beneath the machine. Air leaving the valve V-3 (FIG. 12)

is also directed back to the shuttle valve SV-1 which in turn redirects it to the pilot p-1 of that valve, thereby rendering it unnecessary for the operator to hold the foot valve FV open, once he has initiated the tensioning operation.

Thus under the present invention, if the strap S is fed in a normal manner between the front gripper 30 and the anvil 18, opening of the foot valve FV initiates the strap tensioning cycle, because the strap sensing orifice 103 (FIG. 17) is blocked by the end of the strap S which is held against the anvil surface 92 by the front gripper 30.

Tension Limit Valve Actuation

15 Although enough of a normal cycle has been described in order to understand the short feed lockout of the present invention, in the interest of clarity the operation of the machine up to completion of the tensioning of the strap around a package will be described.

20 FIG. 22 shows the strap pulled tight around the package P by means of the chain drive 42 to the tension wheel 36. This removes the slack in the chain run 42a of the drive chain 42 which swings the idler sprocket 60 to the right against the force of the spring 66, opening the tension limit valve TV as the tab 65 on the rod 64 clears the operator for that valve.

25 Referring to the control diagram of FIG. 13, when the tension limit valve TV opens under the force of its spring, it directs air to the pilot p-2 of the valve V-2, 30 shifting the valve. The pilot p-1 of the valve V-2 is exhausted through the valve V-6. The body port 1 of the valve V-2 now connects the rod end of the linear actuator cylinder 102, to exhaust. Body port 2 of the valve V-2 admits air through a check valve C-V to the piston end of the linear actuator 102, thereby initiating its advance. The speed of the actuator advance is controlled by another throttle valve t.v. connected to the port 1 of the valve V-2.

35 In addition to the above, the body port 2 of the valve 40 V-2 also admits air to the pilot p-2 of the valve V-3, now closed, and connects the pilot p of the valve V-5 to exhaust. The valve V-5 is now closed (by its spring) and connects the tensioning line for motor M to exhaust through the shuttle valve SV-2 and the valve V-5, so that strap tensioning stops after the package has been tightly strapped, as indicated by tension in the run 42a of the chain 42.

45 In addition, body port 2 of the valve V-2 conducts air to the diaphragm actuator 164a for the rear gripper 32, 50 and closes that gripper maintaining the tension about the strap. Finally, pressure from body port 2 of the valve V-2 is directed to the pressure switch PE-2 which closes its contacts (not shown) and associated with the remainder of the cycle.

Remainder of Cycle

55 As mentioned, the details of the remainder of the strapping cycle do not relate to the present invention, and are fully described in the aforesaid Goodley patent. 60 Briefly, the advancing linear actuator 102 advances the cam assembly 100 to retract the tongue 24, advance the heat seal element 140, raise the platen 26 and retract the element 40 while the joint is being formed. The linear actuator then retracts, ultimately restoring the parts to their starting positions. The platen knife 27 will have cut the running portion of the strap and the wrapped package can be removed.

Short Feed Sensing

Having completed a detailed description of the normal operation of a strapping machine embodying the present invention, the operation of the significant portions of a cycle during "short feed" such as when a strap encounters an obstruction, will now be explained.

It is to be understood that the understood "obstruction" is merely a general term that refers to any situation that prevents full feeding of the strap through the yoke 20 and around between the front gripper 30 and the anvil 18. This condition can arise either from an actual physical obstruction to the strap somewhere along its feeding path, to excessive strap curl or to other abnormal strap conditions.

The initiation of a new strap feeding cycle, preparatory to tensioning the strap around the package, has been previously described. For example, feeding of the strap begins in a normal manner as described in connection with the control diagram of FIG. 9A; however, when the short feed sensing control of the present invention operates, it will be assumed that during the feeding operation, the strap encounters an obstruction, as indicated diagrammatically at the control diagram of FIG. 23. This prevents normal feeding of the strap through the yoke, between the front gripper 30 and the anvil and against the anvil stop 19, but the effect of the obstruction indicated in FIG. 23 on the control circuit is the same as the effect of the strap end striking the anvil stop 19, as illustrated in the control diagram of FIG. 10. A loop of strap is developed at the flag 70, the strap limit valve SV opens and the motor M is reversed to remove the loop. When the loop is removed, the conditions previously illustrated and described in conjunction with the control diagram of FIG. 11 takes place. The flag 70 returns to its normal position and the strap limit valve SV recloses, opening the reverse line of the motor M to exhaust and thereby stopping the loop withdrawal. This condition is likewise shown in FIG. 23 which is like the diagram of FIG. 11 for normal operation except that the strap end has encountered an obstruction or the like, instead of striking the stop 19 at the anvil. Since the position of the end of the strap is not ordinarily visible, the usual case is that when the obstruction condition of FIG. 23 takes place, the operator is unaware of that condition.

In order to understand the short feed sensing control of the present invention it should be recalled that as indicated in FIG. 10, before the loop at the flag 70 was removed by opening of the strap limit valve SV, the valve V-1 was shifted to supply air under pressure from the on-off valve 22 to the diaphragm 164 for the front gripper 30 and that the front gripper 30 was thereby closed in order to grip the free end of the strap against the anvil 18. As mentioned, withdrawal of the loop at the flag 70 is indicated in the control diagram of FIG. 23 (corresponding to FIG. 11) and is shown in more detail in the mechanical diagram of FIG. 25, showing the front gripper 30 closed, but not against the end of the strap.

Being unaware of the short feed condition, which is usually the case, the operator will now open the foot valve FV as indicated in the control diagram of FIG. 24. However, since the end of the strap was not trapped between the front gripper 30 and the undersurface 92 of the anvil 18, due to the obstruction, the condition of the enlarged section of FIG. 26 and the still further en-

larged section of FIG. 27 is present. In this condition, although the front gripper 30 is closed, and its serrations 30b are pressed against the undersurface 92 of the anvil, since no strap end is present between these parts,

5 the anvil orifice 103 is not closed and is hence, in effect, open. With the anvil orifice 103 open, air from the air supply flowing through the open foot valve SV and the needle valve NV (FIG. 24) in the line that normally conducts all air from the foot valve FV to the shuttle valve SV-1 for the control valve V-3 is bypassed by the anvil orifice 103. The needle valve NV will have been adjusted so that when the anvil orifice 103 is open, and hence diverts air flowing through the needle valve, the amount of air directed to the shuttle valve SV-1 of the

15 valve V-3 is insufficient to cause the pilot p-1 for the latter valve to shift, as it did in the corresponding case of normal operation shown in the diagram of FIG. 12. Since the control valve V-3 does not shift, under the obstruction conditions of the diagram of FIG. 24, the 20 reverse or tension line connected to the motor M remains at exhaust, instead of receiving air under pressure to reverse the motor and initiate the strap tensioning cycle, as shown in the normal circuit diagram of FIG. 12.

Thus, when the strap S is not fully fed or at least is not fed between the gripper 30 and the anvil 18 during the initial feeding portion of the cycle, even though the operator opens the foot valve SV to initiate tensioning, 25 no tensioning cycle is initiated and hence the strap S, although it is not gripped by the front gripper, is not withdrawn from the yoke and from the wheels 34, 36. The fact that tensioning does not take place when the foot valve FV is opened is a clue to the operator that an obstruction or the like exists. The yoke and other parts of the machine can be inspected and the obstruction removed without need for refeeding the strap back through the wheels 34, 36 and on through the various parts of the apparatus.

30 After the obstruction has been cleared by the operator, feeding is resumed by first opening the on-off valve 22 which sets up the conditions of control diagram FIG. 9. These conditions are, as previously mentioned, de-pressurizing of the pressure switch PE-1 and corresponding energization of the solenoid for the valve V-6. As mentioned, and as shown in the Goodley patent, when the pressure switch PE-1 is de-pressurized, its contacts (not shown) are closed and since they are connected across the electric line in series with the solenoid for valve V-6, the solenoid is energized. The valve V-6 now conducts air to the pilots p-1 of the valves V-1, 35 V-2, shifting them to their original positions shown in FIG. 9.

The operator now re-closes the on-off valve 22 as 40 shown in FIG. 9A which conducts air to the motor M, driving that motor in the feed direction. If the obstruction has been cleared, the feeding and loop removal cycles take place as in FIGS. 10 and 11, after which the foot valve FV is again opened by the operator to initiate a tensioning cycle as shown in FIG. 12.

Having completed a detailed description of the invention as applied to a strapping machine, it can be seen that the short feed sensing device of the present invention senses the short feed condition and prevents subsequent withdrawal of the strap, which has not been gripped by the front gripper, from the machine. This eliminates the need to rethread the strap through the

machine manually after the obstruction or interference has been cleared.

Although the best mode contemplated for carrying out the present invention has been herein shown and described, it will be apparent that modification and variation may be made without departing from what is regarded to be the subject matter of the invention.

What I claim is:

1. Article strapping apparatus of the type comprising a reversible motor driving strap transport wheel means in one direction for feeding a strap through an article receiving yoke and between an anvil and gripper assembly to bring the end of the strap against a stop, means for thereupon closing the gripper to clamp the end of the strap against the anvil, and control means for reversing the motor to cause the transport wheel means to slip the strap free of said yoke and tension the strap about an article within the yoke; the improvement comprising an air orifice in said anvil and gripper assembly which orifice is blocked only when the strap end passes between said anvil and gripper assembly and

the gripper closes, said control means comprising a source of air under pressure, a tensioning initiating valve between said source and said orifice, and means for preventing reverse motion of said motor and said transport wheel means sufficient to withdraw the strap from said yoke when said tension initiating valve is opened and said orifice is open due to failure of the end of the strap to reach said gripper during said strap feeding operation.

2. The apparatus of claim 1, wherein said air orifice is in said anvil and opens toward said gripper, and said gripper has a corrugated jaw that permits escape of air from said orifice when no strap end is present.

3. The apparatus of claim 2, whereby said control means includes a pilot operated valve having a pilot connected in a line from said tension initiating valve for reversing said motor, said orifice being connected to bleed air from said line and an adjustable needle valve in said line between said tension initiating valve and said valve pilot.
